UNITED STATES PATENT OFFICE.

BENJAMIN J. C. HOWE, OF SYRACUSE, ASSIGNOR TO EZEKIEL B. HOYT, OF SKANEATELES, AND HENRY J. HOWE, OF SYRACUSE, NEW YORK.

FIRE-ENGINE.

SPECIFICATION forming part of Letters Patent No. 244,131, dated July 12, 1881.

Application filed December 29, 1880. (Model.)

To all whom it may concern:

Be it known that I, BENJAMIN J. C. HOWE, a citizen of the United States, residing at Syracuse, in the county of Onondaga and State of New York, have invented certain new and useful Improvements in Fire-Engines; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention is in the nature of improvements in horse-power fire-engines; and the invention consists in the peculiar construction, arrangement, and combination of pumps and their operating mechanism, as hereinafter specified and claimed, whereby a simple, effective, and cheap fire-engine is produced, suitable alike for the purposes of extinguishing conflagrations and of pumping water.

In the accompanying drawings, illustrating my invention, in the several figures of which like parts are similarly designated, Figure 1 is a top-plan view of my apparatus. Fig. 2 is a side elevation thereof with the near wheels removed. Fig. 3 is a horizontal longitudinal section, looking upward from below, showing the timing of the pump-pistons to insure a continuous flow or discharge. Fig. 4 is a central vertical section of the pumps. Fig. 5 is a bottom view of the pumps with the lower water-chamber removed, and Fig. 6 is an inner face view of the lower water-chamber removed.

I wish to state at the outset that I am not the first to arrange a number of co-operating pumps in a fire-engine whose pistons are driven by a cam-wheel or by an arrangement of gearing operated by horse-power.

My invention is designed to simplify and improve this old construction; and to this end I employ a frame composed of horizontal longitudinal beams *a*, having cross-pieces *b* and *c* and wheel-supporting trucks *d*.

To the cross-pieces *c* are suitably bolted the pumps *e*, and connected with the pumps, or formed thereon, is a tubular upright projection, *f*, (see Fig. 4,) turned true, and serving as a bearing or axle to receive the hub of the toothed pump-driving wheel *g* and for attach-

ment of the air-chamber *h*. The driving-wheel *g* is adapted to receive the pole *i* of the engine, which may be used to attach the horses used in drawing the engine, for the purpose of driving the pumps when in operation. To the cross-pieces *b* are secured in suitable boxes the shafts *j k* of pinions *l m*, which pinions mesh with the teeth of the driving-wheel *g*, to be driven thereby. On the lower ends of these shafts *j k* are secured cranks or disks *n o* respectively, to which are attached links *p q*, which receive the piston-rods *r s*, and through the media of these wheels or gears, disks, links, and piston-rods the pumps are operated.

Two or more pumps are employed, in accordance with the desired capacity of the engine; and I prefer to use double-acting pumps, as illustrated in Fig. 4.

In the drawings I have shown an arrangement of three co-operating pumps, consisting of three cylinders, *t*, bolted between water-chambers *u v*, each cylinder communicating with each chamber at opposite ends by means of the four flap-valves *w*. These cylinders are provided with heads *t'*, forming water-ways for the valve at opposite ends, between which heads the pistons *x* on the piston-rods *r s* work.

y is the inlet, arranged in the lower water-chamber, *u*, and *z* is the outlet or discharge, connected with the upper water-chamber, *v*. The water-chambers are made to register with the pump-cylinders and accurately fitted thereto by means of holes *a'* in the former, which receive pins *b'* on the latter.

In the operation of my engine the apparatus is suitably braced against movement, as by brace-rods or grapples engaging stakes or the earth, or otherwise, and rotary motion being imparted to the wheel *g*, it is communicated to the pinions *l m*, shafts *j k*, and disks or cranks *n o*, thereby reciprocating the piston-rods *r s* and the pistons, and causing the inflow and discharge of water through the pumps. The links of the piston-rods are so arranged upon their disks or cranks, or the rotation of such disks or cranks is relatively such, that no two of the pistons will be moving in relatively the same path at the same time. (See Fig. 3.) In other words, each piston will be in a different position from the others with relation to its dead-center throughout its stroke, so that the in-

dividual actions of the pumps will be collectively such as to insure a continuous inflow and discharge, and hence the action of the apparatus will be unremitting.

5 This engine may also be worked by hand-power suitably applied to the wheel *g*.

The pumps are arranged about midway of the frame, and hence their weight and that of the driving-wheel above them is better sustained, the apparatus more easily drawn, and the symmetry preserved.

10 Each of the pump-cylinders is in communication with the two water-chambers, but not with each other, and the individual action of 15 the pumps is aggregated in the constant supply of the inlet-chamber *u* and the supply and discharge of the outlet or discharge chamber *v*.

What I claim is—

1. The improved fire-engine described, composed of the horizontal frame *a b c*, two or more connected co-operating pumps, *e*, supported thereupon, the driving-wheel *g*, supported above the pumps upon the axle *f*, rising from said pumps, the pinions *l m*, meshing with said

driving-wheel, the pinion-shafts *j k*, disks or 25 cranks *n o* thereon, and connections for operating the pump-pistons, substantially as described.

2. In a fire-engine, the combination, with the pumps and their operating devices, of the horizontal driving-wheel supported upon an axle, 30 *f*, rising vertically from the pumps and secured in place by the air-chamber *h*, substantially as described.

3. The longitudinal beams *a*, supported upon 35 suitable wheeled trucks and having the cross-pieces *b c*, to support the operative parts of a fire-engine, in combination with the pumps of such engine nested together about midway of said beams, and the driving-wheel arranged 40 above and having its axle upon said pumps, substantially as shown and described.

In testimony whereof I affix my signature in presence of two witnesses.

BENJAMIN J. C. HOWE.
